ABSTRACT: A self-aligning pivot support for church kneelers and like devices in which spaced supporting arms are pivotally mounted for swinging movement on the end and intermediate pew supports. The pivot member is mounted on a supporting bracket structure so as to have universal movements which permit of automatic compensation for slight variations and departures with respect to mounting surfaces and spacing dimensions, a spring operating to urge the pivot member towards a normal position, and resiliently oppose tilting as well as limited axial movement of the pivot member.

SELF-ALIGNING PIVOT SUPPORT FOR CHURCH KNEELER

BACKGROUND OF THE INVENTION

The present invention relates generally to a pivotal support. The invention, although susceptible of general application, is particularly efficacious for the mounting of church kneelers of the type disclosed in U.S. Letters Pat. No. 3,271,074 in which an elongate cushioned bench is provided with spaced arms along its length, these arms being swingably supported by pivots on brackets attachable to the side surfaces of the end and intermediate vertical supports of the church pew or bench. These pivots have in the past been rigidly secured to the mounting or attaching plates, and in many installations problems have arisen due to variations in the spacing distances between the side surfaces of the pew supports or their lack of parallelism when initially installed, warping or other causes. With the fixed type of pivot, as heretofore used, the resulting misalignment even though slight was sufficient in many cases to cause a binding of the pivot so that it was not possible to obtain smooth pivotal movements of the kneeler to its positions of use and nonuse. Under said circumstances, unnecessary and objectionable wear of the pivot members resulted.

In the present invention, this problem is solved by utilizing a unique pivot mounting in which the pivot member is susceptible of universal-tilting and endwise movements from a normal position towards which it is resiliently urged, but which permits automatic self-alignment to compensate for limited variations in the mounting conditions.

SUMMARY OF THE INVENTION

The present invention relates generally to a pivot support bracket of the type utilized for various purposes including use in kneeling benches or kneelers such as connected to church benches or pews, and is more particularly concerned with a pivot bracket in which the pivot is self-aligning.

Having in mind the inherent disadvantages of the present available pivotal mountings, it is one object of the present invention to provide an improved pivot bracket for mounting on a flat surface, wherein the pivot is automatically self-aligning to correct for slight differences and variations in installation conditions.

A further object of the invention is to provide an improved pivot bracket of the foregoing type, which is especially effective for the mounting on church kneeling benches or church pews.

Another object is to provide as a new article of manufacture an improved self-aligning pivot for use with kneeling benches, and the like.

Still another object is to provide a pivot support for church kneelers and for other uses generally which is simple of construction, economical of manufacture, and which provides a unique pivotal mounting which permits limited universal-tilting and endwise movements of the pivot member.

Further objects and advantages of the invention will be brought out in the following part of the specification, wherein detailed description is for the purpose of fully disclosing a preferred embodiment of the invention without placing limitations thereon.

BRIEF DESCRIPTION OF THE DRAWINGS

Referring to the accompanying drawings which are for illustrative purposes only:

FIG. 1 is a perspective view of a church bench or pew having a kneeler pivotally supported on a self-aligning pivot structure embodying the features of the present invention;

FIG. 2 is an enlarged fragmentary view in elevation showing the bracket structure and an associated swingable arm of the kneeler, portions being cutaway to show the cooperative relationship of certain parts;

FIG. 3 is an enlarged sectional view, taken substantially on line 3-3 of Fig. 2; and

FIG. 4 is an enlarged fragmentary view including a transverse section taken substantially on line 4-4 of Fig. 3.

5

DESCRIPTION OF THE PREFERRED EMBODIMENT

Referring more specifically to the drawings, for illustrative purposes, the present invention is shown as being utilized with a conventional church pew 10 which has a usual seat-forming portion and back portion 11, and which is supported upon a plurality of vertical supports which may include an end support as indicated at 12 and one or more intermediate supports as indicated at 13.

10 The kneeler may vary as to details of construction, but for purposes of illustration has been shown herein as including an elongate cushioned bench 14 of rigid construction and supported by means of spaced connected laterally extending arm supports 15-15 which are positioned in this case at the bench ends and are pivotally supported for pivotal or swinging movement in each case by means of a pivot-supporting bracket as generally indicated by the numeral 16. As thus arranged, the kneeler is swingably movable from a position of use as shown in Fig. 1, in which position it is supported upon underlying supporting feet 17, to a raised position of nonuse in which the arms 15 engage against stop members 18 carried by the supporting bracket. In the position of nonuse, the bench is folded up and out-of-the-way to permit free passage of persons between adjacent pews.

15 Referring to Fig. 1, it will be observed that the pivot-supporting brackets for the kneeler arms 15-15 are mounted upon the side surfaces of the pew supports. Also, it will be appreciated that in order for the kneeler to swing freely and without binding, the pivotal movement of the arms must be about an axis which is properly aligned with respect to the mounting surfaces of the pew supports, and that if the surfaces upon which the pivot-supporting brackets are mounted are out of parallelism, warped or otherwise not properly oriented, 20 the use of conventional-type pivot-supporting brackets having rigidly mounted pivots thereon could cause binding and friction which would prevent smooth swinging movement of the kneeler. A very material installation problem may thus arise which can become very time consuming and expensive in order to obtain a proper installation.

25 In the pivot-supporting bracket of the present invention, smooth operation is automatically obtained by providing a resiliently supported pivot member having universal movement, and which will be automatically aligned to a proper position.

30 As shown in Fig. 2, the pivot-supporting bracket 16 is fabricated preferably from a suitable metallic material to provide a generally L-shaped bracket body 19 which is adapted to be mounted on the side surface of a pew support with a surface thereof in face engagement with the side surface, the bracket being secured in position by means of a plurality of holding screws 20. In its normal installed position, the stop member 18 will be at the outermost end of a vertically positioned leg 21, while a horizontally extending leg 22 of the bracket body has at its outermost end a pivot-supporting structure as generally indicated at 23, and which constitutes a primary feature of the present invention.

35 As best shown in FIGS. 3 and 4, the outermost end of the leg 22 is cast or otherwise fabricated to form a shell-like housing structure of generally cylindrical configuration, and which includes an outwardly opening cavity 24 having a surrounding wall structure 25. The surrounding wall 25 extends from a bottom wall 26, and at its outer margin defines a cavity entrance 27. As best seen in Fig. 4, the cavity 24 is transversely rectangular and bounded by wall surfaces 28, 29, 30 and 31 which are in right-angled relation.

40 A pivot support member 32 having a cylindrical body portion 33 at one end is formed with a rectangular head portion 34 at its opposite end which is positioned within the cavity 24

and retained therein by means of a washer member 35 which is held in engagement with an abutment circumferentially extending radial shoulder 36 surrounding the opening 27, by means of a retaining ring 37 held in place by headed over integrally formed studs 38 extending from the shell structure.

The edge periphery of the head portion 34 is rounded on each side, and as contained within the cavity 24 cooperates to retain the pivot-support member 32 against rotation but permits universal-tilting movement of the pivot support member as well as limited endwise movement thereof within the cavity. The pivot-support member has a central threaded bore 39 extending from its outer end into communication with a counterbore 40 which opens in the inner end and forms a seat for one end of a coiled compression spring 41, this spring having its other end engaged over a projection 42 extending from the bottom wall 26 to hold this end of the spring in a fixed location. The spring 41 normally urges the pivot-support member towards an outer limit where the head portion 34 will engage the washer 35. With the universal mounting of the pivot-support member, this member is free to form a self-aligning support for an associated arm 15, even though the plane of swing of this arm is not parallel to the supporting side face of the pew support to which the pivot bracket is attached.

It will be noted that the retaining ring 37 has a central opening 43 which is of greater diameter than the pivot support member 32, thus permitting tilting movement thereof. During such tilting movement, the washer 35 will be laterally shiftable between the shoulder 36 and the retainer ring 37. That is to say, that the washer is not rigidly retained in position, but is free to shift during tilting movements of the pivot-support member.

Within the broad concept of the invention, it is contemplated that the pivot-support member 32 may serve directly as a pivot, or may be attached to an adapter member such as indicated at 44, this adapter being arranged as a component of the associated swingable arm 15 and forming a pivot connection therewith when fixedly secured to the pivot-support member 32. This may be done by providing the adapter with a central bore 45 for the reception of the shank of a securing screw 46 for threaded engagement within the threaded bore 39 of the pivot support member 32. The outermost end of the securing screw 46 has a head end 47 by means of which a suitable tool may be applied for tightening the screw. If desired, the engaged ends of the adapter 44 and the pivot-support member 32 may be provided with engageable radial teeth 48 to retain these members against relative rotation.

From the foregoing description and drawings, it will be clearly evident that the delineated objects and features of the invention will be accomplished.

Various modifications may suggest themselves to those skilled in the art without departing from the spirit of my invention, and, hence, I do not wish to be restricted to the specific form shown or uses mentioned.

I claim:

1. A pivotal support comprising:

- bracket having a mounting surface adapted to engage an associated structure on which the bracket is to be mounted;
- an elongate pivot member;
- means mounting said pivot on said bracket for tilting movements from a position in which the pivot axis is substantially normal to said mounting surface; and
- resilient means opposing said tilting movements and normally tending to retain the pivot axis in said normal position.

2. A pivotal support according to claim 1, wherein said mounting means has parts operative to retain said pivot

member against rotation.

3. A pivotal support according to claim 1, wherein the mounting means supports the pivot member for limited endwise movements, and said resilient means urges the pivot member towards one limit of its endwise movement.

4. A pivotal support according to claim 3, wherein the resilient means urges the pivot member endwise outwardly away from said mounting surface.

5. A pivotal support according to claim 1, wherein the resilient means comprises a compression coiled spring.

6. A pivotal support according to claim 1, wherein the bracket includes wall means surrounding a cavity for receiving one end of the pivot member endwise therein, the wall means and said one end of the pivot member having conformed surfaces retaining the pivot member against rotation, but enabling endwise movement thereof.

7. A pivotal support according to claim 6, wherein the conformed surfaces on said one end of the pivot member extend peripherally of a head portion formed at said one end.

8. A pivotal support according to claim 7, wherein the resilient means comprises a compression spring extending between said head portion and a bottom wall of said cavity.

9. A pivotal support according to claim 8, wherein the spring at its outer end is seated in a recess in said head portion.

10. A pivotal support according to claim 8, wherein the spring at its inner end receives a projection extending from the bottom wall of said cavity.

11. A pivotal support for attaching a swingably mounted arm structure of a church kneeler to a pew surface or the like, comprising:

a bracket adapted for mounting on a flat surface
wall means on said bracket surrounding a cavity having an axis extending at a right angle to the flat surface in the mounted position of the bracket;

means including an elongate pivot member positioned with one end in said cavity, and its opposite end extending outwardly of said cavity for pivotally receiving an end of a kneeler arm thereon, said pivot member having limited generally endwise and tilting movement in said cavity; and

means resiliently urging said pivot member axially of said cavity in an outward direction, and towards a position with its longitudinal axis aligned with the cavity axis.

12. A pivot support according to claim 11, wherein said one end of the pivot member comprises a multisided head portion, and the wall of said cavity is peripherally conformed to said head portion, whereby the pivot member is retained against rotation.

13. A pivotal support according to claim 12, including a compression spring extending between said head portion and a wall of said cavity acting to urge said pivot member outwardly of said cavity.

14. A pivotal support according to claim 13 including retaining means at the outer end of said cavity engageable by the head portion of said pivot member under the action of said spring.

15. As an article of manufacture, a pivot bracket comprising:

a bracket structure adapted for mounting on a flat surface; a self-aligning pivot member supported on said bracket for universal-tilting movements, and limited endwise movements from a predetermined normal position with its pivotal axis extending perpendicular to said flat surface; and

means for restoring said pivotal member from a displaced position to its normal position including means resiliently urging said pivot member towards said normal position.
